UNITED STATES PATENT OFFICE.

HARRY E. PARSHALL, OF WHEELING, WEST VIRGINIA.

COOLING, STIRRING, AND DISPENSING VESSEL.

1,095,517.

Specification of Letters Patent.

Patented May 5, 1914.

Application filed October 19, 1912. Serial No. 726,845.

To all whom it may concern:

Be it known that I, HARRY E. PARSHALL, a citizen of the United States, residing at Wheeling, in the county of Ohio and State 5 of West Virginia, have invented certain new and useful Improvements in Cooling, Stirring, and Dispensing Vessels; and I do hereby declare the following to be a full, clear, and exact description of the invention, such 10 as will enable others skilled in the art to which it appertains to make and use the same.

This invention relates to cooling and dispensing apparatuses and it more particularly relates to an improved cooling, stirring and dispensing vessel.

An object of the invention is to provide a vessel or container of this character, which is especially adapted for cooling and dispensing buttermilk or the like.

Another object of the invention is to provide, in a cooling vessel of this character, a combined ice container and liquid stirrer.

Another object of the invention is to provide a thoroughly heat-insulated vessel having an ice container in the center thereof and having a space around the ice container, in which any desired liquid may be contained and cooled.

Another object of the invention is to provide an apparatus of this character which may be quickly and easily dismembered, for thoroughly cleaning the same, and which may be quickly and easily assembled for use.

Other objects and advantages may be recited hereinafter and in the claim.

The accompanying drawing shows a central vertical section of my device.

The liquid receptacle 5 is preferably of cylindrical form and surrounded by any proper heat-insulating material 6, which may extend entirely around and under said receptacle. The insulating material 6 is enclosed within an outer casing 7. The casing 7 is preferably provided with a bottom 8 of non-corrosive material, and the bottom portion of the casing is seated upon a base 9, having legs 10 and having an upstanding peripheral flange 11. The casing may be secured on the base 9, but is preferably removably seated thereon. A pivot-bearing 12 is secured to the bottom 13 of the container, and supported upon this pivot-bearing or block, through the medium of a pivot 14, is an ice receiver 15, said pivot being se-

cured to the concavo-convexed bottom 16 of the ice receiver. The cover of the container and casing consists of a lower cover member 17 and an upper cover member 18, said lower cover member being centrally apertured, and being provided with an annular flange or upper cover seat 19 around its central aperture. The upper cover member is provided with a peripheral flange 20 which is normally seated against the flange 19, and said upper cover member is provided with a central aperture which constitutes a bearing for a crank shaft 21, having a hand crank 22 on its upper end, and having its lower end non-rotatably secured to a spider 23, said spider being fitted within the upper end of the ice receiver 15, and may be either permanently or removably secured therein. The upper periphery of the ice receiver fits snugly and removably within the central aperture of the member 17, so that said cover member 17 may be removed without removing the ice receiver. Secured on the outer surface of the ice container is a number of stirring blades 24, said stirring blades being inclined at an angle of approximately twenty-eight degrees.

An aperture 25 is provided at the bottom of the container and casing, and in this aperture is seated a flanged and screw-threaded tube 26, one or more nuts 27 being employed for securing said tube within the aperture 25. An outer valve element 28 is screw-threaded into the tube 26, and is provided with a central inwardly tapered bore 29 and an outlet opening 30 which communicates with said tapered bore. A tapered and apertured valve closure 31 fits snugly and rotatably within the bore 29, and is provided with an aperture 32 which communicates with the tube 26 and with the outlet 30. The valve closure 31 is formed with a handle 33, by means of which it may be rotated, for bringing the apertures 30 and 32 alternately into and out of registration. A centrally apertured cap 34 is screw-threaded on the outer end of the valve member 28, and the handle 33 extends through the central aperture of the cap 34. It will be seen that, by tightening the cap 34, the valve closure 31 may be tightened within its seat, while if the cap 34 is removed, the valve closure may easily be withdrawn for cleaning and sterilizing. It is also obvious that the member 28 may be quickly and easily removed 110

for cleaning and sterilizing, and when removed, the tube 26 is rendered easily accessible for cleaning. When it is desired to dismember the apparatus, the shaft 21 may be withdrawn, and the top members 17 and 18 may then be removed, whereupon the ice receiver can be lifted from its pivotal seat.

When it is desired to fill the container, the valve must first be closed, and milk may then be poured into the container 5, either before or after the receiver 15 has been filled with ice and placed on its pivot seat, whereupon the cover members and handle may be properly placed. If it is desired to recharge the ice receiver without removing it from the container, the cover member 18 and shaft 22 may be removed, whereupon ice may be introduced into the receiver 15, without danger of ice or other foreign matter entering the milk.

It is well known that after buttermilk has been undisturbed for a short while, the lighter particles thereof will rise, while the heavier particles will settle toward the bottom, so that, unless it is stirred before being drawn, the quality of the first which is drawn will differ from the last. The present invention obviates this difficulty by means of the stirring mechanism which consists of the blades 24 which are mounted to rotate with the container 15, so as to raise and thoroughly mix the heavier portions of milk with the lighter portions thereof. One or two turns of the handle or crank 22 will suffice for thus mixing the buttermilk before it is drawn or dispensed.

It will be seen that I have provided a device of this character which is fully capable

of attaining the foregoing objects, and in a thoroughly practical and efficient manner.

I do not limit my invention to the exact details of construction, combination and arrangement of parts, as herewith illustrated and described, but my invention may only be limited by a reasonable interpretation of the claim.

I claim:—

A cooling and stirring and dispensing apparatus providing a container having double walls, a receiver rotatably mounted upon a bearing in said container and spaced therefrom and having blades upon its outer surface, a cover detachably secured on said container and having downwardly extending flanges engaging the inner and outer walls of said container, and having a central opening therein, an upwardly extending vertical flange on said cover surrounding said opening, the upper end of said receiver being beaded and terminating in said opening, the circumferential periphery only of said beading being rotatably received by said flange, a spider secured to the upper end of said receiver whereby ice may be put into and removed therefrom without disturbing said receiver, and means secured to said spider for rotating said receiver with said flange as a bearing.

In testimony whereof I have signed my name to this specification in the presence of two subscribing witnesses.

HARRY E. PARSHALL.
